Fig. 3.

UNITED STATES PATENT OFFICE.

IZA NELSON MERCER, OF WELLSBURG, WEST VIRGINIA.

GRAPPLE.

Application filed April 10, 1922. Serial No. 551,245.

To all whom it may concern:

Be it known that I, IZA NELSON MERCER, a citizen of the United States, residing at Wellsburg, in the county of Brooke and State of West Virginia, have invented certain new and useful Improvements in Grapples, of which the following is a specification.

My invention has reference, in general terms, to load engaging devices or grapples for use with cranes, derricks and the like, and more particularly it is designed to provide a grapple wherein shifting or accidental displacement of the load is prevented through the medium of clamping jaws, one of which is adapted to exert automatically a gripping but positive action commensurate with the dead weight of the load.

In lifting and transporting heavy and bulky objects by means of cranes or derricks it frequently happens that the load becomes disengaged from the grapping mechanism and in falling causes great damage to property and sometimes loss of life. This is generally caused when the grapple of the hoist or derrick strikes some protruding object or is given a vibratory movement.

One of the objects of my invention is to provide a grapple, the jaws of which are automatically locked in a positive gripping position with respect to a load through the instrumentality of the load when the same is raised from the ground. The mechanism accomplishing this purpose is so arranged that shocks received in transporting the load will not affect the locking members. Furthermore, it sometimes occurs that in lowering a load one edge or portion may momentarily rest on some obstruction thereby causing the load to be inclined at an angle, which is generally sufficient to cause the load to slip from the retaining jaws and fall to the ground. I overcome this difficulty by providing a plurality of locking members some of which will positively retain their locking action until the operator of the hoist has an opportunity to again raise the load clear of the obstruction. Means are also provided for automatically holding the sliding jaw in inoperative position when the load has been released.

To these and other ends, my invention consists in the construction, arrangement and combination of parts described herein-after, illustrated in the drawings, and point-

ed out in the claims forming a part of this specification.

One embodiment of my invention is represented by way of example in the accompanying drawings, wherein:

Figure 1, is a side elevation of the grapple assembly.

Figure 2, is an end view of the same.

Figure 3, is a front elevation of one of the clamping elements.

Figure 4, is a view at right angles to Figure 3, and

Figure 5, is a detail perspective of the lower end of one of the clamping elements.

Figure 6, is a modification of the levers.

Referring to the drawings wherein like characters of reference designate like or similar parts, (1) designates a cable which is suspended from a crane or derrick (not shown). Attached to the lower terminal of the cable (1) are chains (2) the free ends of which are secured in sockets (3) placed on each end of a cross bar (4). The cross bar (4) carries a plurality of transverse supporting arms (5) each of which is provided adjacent its extremities with grooves (6) which are adapted to seat a bracket (7) carrying a ring (8). Suspended from each ring (8) by means of chains (9) are locking assemblies which for convenience will hereinafter be referred to as the clamps. The clamps are identical in construction and operation and for the sake of clarity only one will be described in detail.

The fixed clamping element of my grapple consists in a frame generally designated by (10) formed with two spaced apart, parallel side beams or uprights (11) and (12) connected at their lower ends by a transverse bar (13). The upper ends of the uprights (11) and (12) are bolted or riveted between plates (14) formed each with a semi-circular cut-away portion to permit access therebetween. Upon the lower ends of each of the uprights (11) and (12) are integrally formed beveled teeth (15) and (16) respectively, which extend outwardly at right angles from the uprights for disposition beneath a load to be lifted.

The adjustable element of my grapple consists in a beam (17) arranged for sliding movement between the uprights (11) and (12) and said beam is formed with racked side faces (18) for engagement with the beveled ends of opposed levers (19) pivot-

ally mounted between the plates (14). The levers (19) serve in a capacity resembling pawls engaging the rack faces of the beam (17) to move the beam downwardly. Upon 5 the lower end of the beam (17) is formed a beveled tooth (20) for engagement with a load disposed upon the teeth (15) and (16) to positively hold the same in place. A suitable guide collar (21) is mounted on 10 the beam (17) to hold the beam securely in position between the uprights (11) and (12).

The chains (9), hereinbefore referred to, are connected with the outer extremities of 15 the levers (19) so that the dead weight of a load engaged between the teeth (13), (16) and (20) will cause the levers to move on their axes to force the beam (17) downwardly thereby increasing the gripping action 20 upon the load. Furthermore, a latch (22) is secured for swinging movement upon the forwardmost of the plates (14), and is provided with a pronged head (23) having a beveled face (24). The latch 25 serves to hold the beam (17) in an inoperative position when so desired and normally it will assume a vertical position.

In operation my device functions as follows: When it is desired to apply my grapping mechanism to a heavy or bulky object 30 the fixed jaws are allowed to rest on the ground with a slack in the chains (9). The sliding jaws are each grasped at their uppermost portions and are raised until the 35 tooth strikes the beveled face on the pronged head of the latch. This will cause the latch to be forced out of the path of the tooth until it is clear, when by its own 40 weight and due to its pivotal attachment the pronged head will swing beneath the tooth to hold the sliding jaw in inoperative position. When all of the sliding jaws have 45 been raised to inoperative position the fixed jaws are forced beneath the load. Then by 50 releasing the latches the sliding jaws will of their own weight fall to proper position on the upper surface of the load. When the cable (1) is raised the slack will be taken up from the chains (9), and the 55 chains (9) being secured to the lever arms will turn the lever arms on their pivots thereby exerting a downward pressure on the beam of the sliding jaw. The tension 60 of the chains (9) will be dependent on the weight of the load being hoisted and the force exerted upon the sliding jaws will consequently be proportional to the weight 65 of the load. When the grapple is to be disconnected from the load the sliding jaws are raised until the latches swing to operative position to retain them in the raised position. The fixed jaws are then removed 70 from beneath the load leaving the grapping mechanism in inoperative position and ready 75 for attachment to another load.

The beveled faces on the teeth of the fixed jaw are to facilitate their insertion beneath a load. Occasion may arise when it will not be necessary to utilize the locking action in which event the sliding jaw 70 may be allowed to drop until it rests on the bar (13). The beveled face on the tooth of the sliding jaw is to permit the ready application of the device when used in this manner. 75

The primary purpose of the chains (2) is to absorb shocks caused by striking obstructions when raising a load. No matter how severe a shock may be imparted to the chains (2) the locking action will not be 80 affected. 85

If an obstacle is encountered while lowering a load the load will either rest upon the obstacle or be caused to tilt until it is permitted to slip free, the latter case being the only one it becomes necessary to provide for. By providing a plurality of sets of clamps there will always be a majority of such members which will retain their locking action and thus support the 90 load. 95

Figure 6 shows a modification of the levers (19) in which a lever arm is loosely mounted in the engaging element.

While in the foregoing there has been illustrated and described such combination and arrangement of elements as constitute the preferred embodiment of my invention, it is nevertheless desired to emphasize the 100 fact that interpretation of the invention should only be the conclusive when made in the light of the subjoined claims. 105

Having described my invention and its objects with such attention to detail as will thoroughly acquaint one skilled in the art with its construction and advantages, I 110 claim—

1. A grapping mechanism comprising a cross bar, means secured to the ends of the cross bar for attaching it to a cable, a plurality of transverse supporting arms carried by the cross bar, opposed clamps flexibly suspended from each supporting arm, each of said clamps including a fixed and a movable jaw and means for automatically locking the movable jaw in gripping position when supporting a load. 115

2. A grapple comprising a frame formed with load engaging members, a beam movably mounted upon the frame and formed with a load engaging member, and means for automatically actuating the beam to increase the pressure upon the load as the weight of the load is increased. 120

3. A grapple comprising a frame, formed with load engaging members, a beam movably mounted upon the frame and formed with a load engaging member, levers on the frame for engagement with the beam and said levers connected with the source of 125 130

power to move the beam to grip the load as the load is raised.

4. A grapple comprising a frame formed with load engaging members, a beam mov-
5 ably mounted upon the frame and formed with a load engaging member, said beam having racked faces, and levers engaging the racked faces of the beam to move the same downwardly under the weight of the
10 load.

5. A grapple comprising a frame, a movable member carried by the frame, a catch for retaining the movable member, and means connected with the frame for actuating the movable member.

6. A grapple comprising a frame formed with a pair of parallel, spaced, side rails having load engaging members on their lower ends, a movable beam carried between

the side rails and formed with racked faces, 20 a pair of levers engaging the teeth formed by the racked faces, and flexible means connecting the levers with a source of power.

7. A grapple comprising a frame formed with load engaging members, a beam mov- 25 ably mounted on the frame and formed with a load engaging member, a pair of levers engaging the beam to move the same to cause the load engaging member thereon to approach the first mentioned load engaging 30 members, a supporting bar, flexible members connecting the levers with the supporting bar, and flexible members connecting the supporting bar with a source of power.

In testimony whereof I affix my signature hereto.

IZA NELSON MERCER.
